(57) **CLAIM**

The ornamental design for an adhesive spray nozzle as shown and described.

DESCRIPTION

FIG. 1 is a perspective view of an adhesive spray nozzle showing the new design for an adhesive spray nozzle.

FIG. 2 is a right side view thereof;

FIG. 3 is a left side view thereof;

FIG. 4 is a front view thereof;

FIG. 5 is a top view thereof;

FIG. 6 is a bottom view thereof;

FIG. 7 is a rear view thereof; and,

FIG. 8 is an enlarged view of the area within circle 8 of FIG. 1.

The portions of the “adhesive spray nozzle” in FIGS. 1-8 shown in broken lines are included to show features that form no part of the claimed design.

1 Claim, 8 Drawing Sheets
